UNITED STATES PATENT OFFICE.

ISAAC A. WATROUS, OF BRIDGEPORT, CONNECTICUT.

ELECTRICALLY-OPERATED MACHINE FOR SCRAPING IRREGULAR WOODEN SURFACES.

1,392,543.

Specification of Letters Patent.

Patented Oct. 4, 1921.

Application filed April 9, 1921. Serial No. 460,070.

To all whom it may concern:

Be it known that I, ISAAC A. WATROUS, a citizen of the United States, residing at the city of Bridgeport, in the county of Fairfield and State of Connecticut, have invented certain new and useful Improvements in Electrically-Operated Machines for Scraping Irregular Wooden Surfaces; and I do declare the following to be a full, clear, and exact description of the invention, such as will enable others skilled in the art to which it appertains to make and use the same.

This invention relates to certain new and useful improvements in butcher block cleaners and while particularly directed to the cleaning of butcher blocks is nevertheless not so limited in its use, but may be employed with equal facility in scraping or cleaning work benches, or any other surface of irregular shape, *i. e.*, convex or concave or alternative combinations of the two.

The primary object of the invention is to provide a device of this type which involves a preferably electrically rotated cutter, the latter being bodily resiliently mounted and in turn having resiliently mounted cutting teeth so that what might be termed a compound resiliency results, enabling the cutters to seek and conform themselves to the irregular surfaces of butcher blocks or the like.

A further object of the invention is to provide a scraper of this type wherein the cutters can be manually and selectively moved into and out of operative position, and when in operative position can be moved with adjustable pressure into contact with the work, thus allowing the operator to regulate the depth of the scraping action of the cutters, or in other words to allow the cutters to have a fine or a coarse cutting effect.

The invention still further aims to provide a device of this type which is compact and simple and in which the same may be propelled by one hand of the operator over the surface and to also effect closing of the motor switch by use of that hand of the operator incident to the propelling or guiding movement of the device.

In the drawings:

Figure 1, is a side elevation of the invention partly broken away and in section;

Fig. 2 is a fragmentary bottom plan view showing the preferred form of cutter;

Fig. 3 is an enlarged fragmentary sec-

tional view showing the ball bearing rings for the cutter carrying rod;

Fig. 4, is a bottom plan view of a modified form of cutter, and

Fig. 5, is a side elevation of Fig. 4.

In proceeding in accordance with the present invention, a frame 1 is employed having a smooth bottom face so as to easily ride over the surface to be cleaned. A motor 2 is mounted on the frame 1 and has a fly wheel 3 and a bevel gear 4 on its shaft. The front end of the frame is formed with a housing having a tubular part 5 in which a vertically slideable rod or shaft 6 is mounted. A threaded bearing plug 7 closes the upper end of the housing and has an aperture through which the shaft 6 passes. A collar 8 is rigidly affixed to the shaft 6 and slides therewith within the tubular part 5 of the housing, ball bearing rings 9 and 10 being engaged about the shaft and disposed on opposite sides of the collar. The lower end of the tubular housing part 5 is formed with a spring seat 11 on which engages the lower end of a coil spring 12, the opposite end of which spring bears against the ball ring 10. It will thus be noted that the shaft 6 is vertically slideable and is normally held upwardly and tensioned by the spring 12.

The lower end of the shaft has key-ways 13 in which are slidably received the ends of threaded pins 14 borne by the hub of a bevel gear 15 which latter meshes with and is driven by the bevel gear 4 of the motor. Below the tubular part 5 the housing is formed with a seat 16 in which engages a thrust bearing 17 that supports the bevel gear 15.

A cutter 18 is secured to the lower end of the shaft 6 and operates in a chambered part 19 formed in the bottom face of the body 1, the chamber being sufficiently deep so that the cutter will normally lie above the bottom face of the body or be held by the spring 100 completely within the chamber.

The cutter 18 is preferably of S-shape and is mounted on a hub 20 carried by the lower end of the shaft 6.

The arms of the cutter are slotted at 21, the slits being of varying lengths thereby to provide a series of separate and independent teeth, the ends of which are turned downwardly at right angles at 22, to form scraping or cutting edges.

The cutter is made of relatively thin material having spring properties and is unsup-

ported excepting at its point of attachment to the hub, so that the teeth are resiliently mounted and may have movement independent of one another.

5 In the modified form of the cutter, depicted in Figs. 4 and 5, three arms 23 are provided each being attached by screws 23 to a supporting disk 24 which acts as a backing for the arms, the arms being offset at 25 so as to permit same to have limited movement toward the disk before engaging and being held by the latter. The arms are formed of spring material and have angular teeth 26 of varying lengths as in the instance of the cutter 18. A circular handle 27 is swiveled onto the upper end of the shaft 6, for a purpose shortly to be described. Carried by the outer end of the frame is an ordinary handle 28 similar to a carpenter's plane handle, and adjacent the inner face of the handle is a pivoted trigger 29 which carries a fiber or other insulated pin 30 that operates against a spring member 31, which constitutes one terminal, to force the latter into contact with the other terminal 32, so as to close the circuit and operate the motor. The positive and negative wires 33 for these terminals pass out through the top of the handle 28 and are connected with any source 30 of electricity, the cords being long enough to allow free operations of the scraper, after the manner of an ordinary electric hand iron.

35 The operator grasps the handle of the trigger and by pressing thereon closes the circuit, causing the motor to be operated and the cutters thereby revolved. With this same hand the operator pushes the device over the block in any direction desired steering it by placing his other hand upon the handle 27 and pressing down on the latter, the downward pressure bringing the cutters into more or less intimate contact with the block. When the operator releases his hand 40 45 the natural squeezing action thereof in gripping handle 28 will release the trigger 29, opening the switch and stopping the motor.

From the foregoing it will be seen that the operator by regulating the manual pres-

sure exerted on the handle 27 can correspondingly regulate the degree of engagement of the teeth with the surface being operated upon, or in other words cause a coarse or fine scraping or cutting action of the teeth on such surface. 50 55

Further, the cutter carrying shaft 6 is not only resiliently mounted, but the individual teeth themselves are independently movable or resilient in addition to each arm being bodily resiliently mounted, thus obtaining a compound resilient action of the parts to thereby accommodate themselves to the irregularities of the surface being scraped. Any suitable abutment *a* on this shaft 6 checks undue upward movement thereof. 60 65

What is claimed is:

1. In a surface scraper, a body having a vertical propelling handle, a motor on the body, a switch having a vertical part adjacent the handle for controlling the motor and for engagement by the fingers of the hand of the operator which grasps the handle, a vertically movable spring tensioned scraper carrying member borne by the body, means to drive said member from the motor, a scraper having resilient teeth carried by said member, and a swiveled handle connected to said member for guiding the device and for regulating the degree of engagement of the scraper with the surface by mere depression of the handle and upon release to allow the spring to instantly raise the scraper out of engagement with the surface. 70 75 80

2. In a hand controlled surface scraper, a body having a motor thereon and having a handle at one end, motor control means associated with the handle to be gripped with the latter in one hand of the operator, and a depressible tensioned scraper at the other end of the body having a swiveled handle for engagement with the other hand of the operator, whereby to enable the device to be both guided across the surface being scraped and the degree of scraping regulated by downward pressure on the handle. 85 90 95

In testimony whereof I affix my signature hereto.

ISAAC A. WATROUS.
